UNITED STATES PATENT OFFICE.

CHARLES SEAVER HURD, OF NEWARK, NEW JERSEY.

DESIGN FOR A BRACELET.

No. 37,767.

Specification for Design.

Patented Jan. 2, 1906.

Application filed October 30, 1905. Serial No. 285,192. Term of patent 3½ years.

To all whom it may concern:

Be it known that I, CHARLES SEAVER HURD, a citizen of the United States, and a resident of Newark, in the county of Essex and State of New Jersey, have invented a new, original, and ornamental Design for a Bracelet, of which the following is a specification, reference being had to the accompanying drawing, forming a part thereof.

The figure is a perspective view of a bracelet, showing my new design.

I claim—

The ornamental design for a bracelet, as shown.

CHAS. SEAVER HURD.
